UNITED STATES PATENT OFFICE.

HENRY NOAH, OF BAXTER, IOWA.

ROTARY STEAM-ENGINE.

SPECIFICATION forming part of Letters Patent No. 793,216, dated June 27, 1905.

Application filed April 12, 1905. Serial No. 255,857.

To all whom it may concern:

Be it known that I, HENRY NOAH, a citizen of the United States of America, and a resident of Baxter, Jasper county, Iowa, have invented a new and useful Rotary Steam-Engine, of which the following is a specification.

The object of this invention is to provide an improved construction for rotary steam-engines.

10 A further object of this invention is to provide an improved valve-motion for rotary steam-engines.

My invention consists in the construction, arrangement, and combination of elements, 15 hereinafter set forth, pointed out in my claims, and illustrated by the accompanying drawings, in which—

Figure 1 is an end elevation of the complete engine. Fig. 2 is a vertical section transversely of the engine-shaft. Fig. 3 is a vertical section longitudinally of the engine-shaft. Fig. 4 is a plan of the complete engine.

In the construction of the engine as shown the numeral 10 designates a base member, and 25 11 a cap member, which members conjunctively form a cylinder. The cylinder members 10 11 are formed with flanges 12 13, projecting laterally from their outer surfaces adjacent each other and adapted to be connected 30 by bolts to join the members rigidly yet detachably. Cylindrical steam-chambers 14 15 are formed in the cylinder members 10 11, one-half of each chamber in each member, and said chambers are placed end to end and spaced 35 apart. An engine-shaft 16 is mounted for rotation in alining bearings formed in the central portions of the meeting margins of the cylinder members 10 11, and said shaft extends through the central portions of the members 40 which separate the steam-chambers and is centrally of said steam-chambers. Ingress-ports 17, one of which is shown in Fig. 2, are formed in the cap member of the cylinder and enter the steam-chambers 14 15 a little to the 45 rear of the vertical plane of the engine-shaft 16. Steam is supplied to the ingress-ports 17 through a pipe 18, provided with branches 19 20, leading, respectively, to said ports, the supply-pipe being controlled in a common manner

by a valve 21. An oscillating valve 22 or 23 50 is mounted across each of the ingress-ports 17 and is so arranged as to cut off said port when oscillated slightly in either direction. Egress or exhaust ports 24 25 are formed in the base member 10 of the cylinder and lead from the 55 steam-chambers 14 15 a little to the rear of the vertical plane of the engine-shaft 16.

Piston-heads 26 27, each circular in form, are mounted rigidly on the engine-shaft 16 and within the steam-chambers 14 15, said 60 heads being of sufficiently less diameter than the chambers to provide space for the steam. The piston-heads 26 27 are provided with lugs 28 29, radially thereof, and equipped with suitable packing 30. The lug 28 on the head 26 65 is arranged diametrically opposite the lug 29 on the head 27.

Backing-pistons 31 32 are mounted for vertical reciprocation in slide-bearings in the cap member 11 of the cylinder and are arranged 70 to move rectilinearly across the upper portions of the steam-chambers and across grooves 33 in the peripheries of the piston-heads 26 27. Each of the backing-pistons 31 32 is provided with rollers in its side margins adapted for 75 rolling contact at times with the peripheral flanges of the piston-heads, and each backing-piston also is provided with suitable packing. The backing-pistons 31 32 are in the vertical plane of the engine-shaft 16 and are connected 80 by pitmen 33 34 to oppositely-extending cranks 35 36 on a shaft 37, said shaft being mounted for oscillation in bearings 38 on the cap member 11. Oppositely-extending cranks 39 40 are formed on the end portions of the 85 shaft 37 and are connected by pitmen 41 42 to bell-crank levers 43 44, fulcrumed on stub-axles 45 46, seated in and extending outwardly from the ends of the cap member 11. The stub-axles 45 46 are parallel with and above 90 the end portions of the engine-shaft. Disks 47 48 and 49 50 are mounted loosely on the stub-axles 45 46 and are connected by rods 51 52 53 54, respectively, to the outer end portions of the oscillating valves 22 23, one pair 95 of disks and rods to each valve, and the individuals of each pair of rods connecting on opposite sides of the axis of the respective valve.

Each of the disks is formed with a lug 55 or 56, projecting generally downward from its periphery.

5 Circular wheels 57 58 are mounted rigidly on the engine-shaft 16 outside the cylinder, and each wheel is provided with lugs 59 60, projecting radially from its periphery and spaced apart. The wheels 57 58 are provided with cam-faced bosses 61 62 on their outer 10 surfaces, and rollers 63 64 on the extremities of the longer arms of the bell-crank levers 43 44 ride at times on the faces of said bosses.

The operation of the engine is as follows: Preliminary to starting the engine the parts 15 are positioned as shown, the ingress-port 17, leading to the steam-chamber 14, being open and the other ingress-port being closed and the backing-piston 31 being down and the other, 32, being up. The valve 21 is then 20 opened to supply steam through the open port 17 to the chamber 14, and said steam enters said chamber and exerts its force on the lug 28 and backing-piston 31, thereby moving the lug and rotating the head 26 and engine-shaft. 25 Steam continues to enter the chamber 14 until the lug 60 engages the lug 56 and oscillates the disk 48, whereupon said disk acts through the rod 51 and oscillates the valve 22 to close the port in which said valve is mounted. The oscillation of the valve 22, as described, effects a reverse movement of the disk 47 through the rod 52 and places the lug 55 in position to be engaged by the lug 59 a little later, such later engagement reopening 35 the valve 22. After the steam is cut off by the valve 22 it exerts its expansive force solely until the lug 28 passes the exhaust-port 24, where it exhausts. Coincidently with the exhaustion of steam from the chamber 14 the circular face of the boss 61 releases the bell-crank lever and permits the circular face of the boss 62 to engage the other lever and oscillate the shaft 37 (just following the opening of the valve 23 by the lug 59 on the wheel 45 58 engaging a lug 55 on the disk 49) to the end of shifting the relative positions of the backing-pistons through the medium of the cranks 35 36. Then steam is applied to the lug 29 of the piston-head 27 to the rotation of 50 the latter head and engine-shaft. The movements just described are alternated continuously, thus applying steam alternately to the piston-heads and maintaining an automatic operation of the ingress-valves and backing-pistons.

55 I claim as my invention—

1. In a rotary engine, two piston-heads arranged for alternate actuation, an engine-shaft adapted for rotation by said piston-heads, 60 valves mounted for oscillation and controlling the entrance of steam to said piston-heads, backing-pistons mounted for reciprocation alternately, and devices on the engine-shaft adapted to oscillate said valves and recipro-

cate said backing-pistons, said devices comprising wheels on the engine-shaft, lugs on said wheels, stub-axles, disks on said stub-axles and flexibly connected to said ingress-valve, and lugs on said disks engaged by lugs on the wheels. 65

2. In a rotary engine, oppositely-arranged piston-heads, an engine-shaft common to said heads, valve-controlled ingress-ports, oppositely-arranged backing-pistons, a crank-shaft controlling said pistons, and engaging devices 70 on said engine-shaft adapted to act at times on the valves and crank-shaft, said devices comprising wheels on the engine-shaft, lugs on said wheels, stub-axles, disks on said stub-axles and flexibly connected to said ingress-valve, and lugs on said disks engaged by lugs on the wheels. 75

3. In a rotary engine, piston-heads formed with grooved peripheries, lugs extending radially from said heads, backing-pistons arranged for reciprocation into and out of said grooved peripheries in opposition to said lugs, valve-controlled ingress-ports, and engaging devices actuated by said piston-heads to operate said valves and backing-pistons, said devices comprising wheels on the engine-shaft, lugs on said wheels, stub-axles, disks on said stub-axles and flexibly connected to said ingress-valve, and lugs on said disks engaged by lugs on the wheels. 80

4. In a rotary engine, an ingress-valve mounted for oscillation, an engine-shaft, a wheel on said shaft, lugs on said wheel a stub-axle, disks in said stub-axle and flexibly connected to said ingress-valve, and lugs on said 85 disks adapted for engagement by the lugs on the wheel. 90

5. In a rotary engine, backing-pistons mounted for rectilinear reciprocation, a crank-shaft mounted for oscillation, oppositely-extending cranks on said shaft connected respectively to said backing-pistons, oppositely-extending cranks on the ends of said shaft, an engine-shaft, cams on said engine-shaft, bell-cranks flexibly connected to said end cranks, 100 and rollers on said bell-cranks engaged by said cams. 105

6. The combination of the backing-pistons, the crank-shaft, the pitmen connecting said pistons and crank-shaft, bell-crank levers, 115 pitmen connecting said levers and crank-shaft, an engine-shaft, cams on said engine-shaft, adapted to engage and oscillate said bell-crank levers, an ingress-valve, disks oppositely connected thereto, wheels on the engine-shaft, 120 lugs on the disks, and lugs on the wheels adapted to engage the lugs on the disks.

Signed by me at Baxter, Iowa, this 1st day of April, 1905.

HENRY NOAH.
